US00D528112S

(12) **United States Design Patent** (10) Patent No.: **US D528,112 S**
Park et al. (45) Date of Patent: **** Sep. 12, 2006**

(54) **PERSONAL COMPUTER**

(75) Inventors: **Sun Jung Park**, Seoul (KR); **Byung Mu Huh**, Seoul (KR); **Kyung Min Kim**, Seoul (KR)

(73) Assignee: **LG Electronics Inc.**, Seoul (KR)

(**) Term: **14 Years**

(21) Appl. No.: **29/232,558**

(22) Filed: **Jun. 22, 2005**

(30) **Foreign Application Priority Data**

Dec. 30, 2004 (KR) 30-2004-0040819

(51) **LOC (8) Cl.** **14-02**

(52) **U.S. Cl.** **D14/349**

(58) **Field of Classification Search** D14/308, D14/348-356; D13/162, 184, 199; 312/223.1-223.2, 312/265.6; 360/99.01-99.12; 369/34.01, 369/36.01; 361/680-686

See application file for complete search history.
